UNITED STATES PATENT OFFICE.

WILLIAM GADKE, OF PHILADELPHIA, PENNSYLVANIA.

TIMER FOR IGNITION SYSTEMS.

1,181,867.

Specification of Letters Patent.

Patented May 2, 1916.

Application filed June 3, 1914. Serial No. 842,685.

To all whom it may concern.

Be it known that I, WILLIAM GADKE, a citizen of the United States, residing in Philadelphia, Pennsylvania, have invented 5 certain Improvements in Timers for Ignition Systems, of which the following is a specification.

One object of my invention is to provide a novel mechanism particularly designed 10 for successively making and breaking an electric circuit, and more especially the primary circuit of the ignition system of an internal combustion engine.

It is further desired to provide a timer 15 which, in addition to being relatively simple, substantial and reliable in operation, shall have its parts so arranged and constructed that its action is substantially constant regardless of the speed at which its 20 driving member is operated; that is to say, its contact members shall be actuated to make and break the circuit in which they are included at a definite time after the slide member has been actuated by the driving 25 member, regardless of the speed of the latter.

I further desire to provide a timer in which the parts shall be so disposed and constructed that they shall be practically 30 unaffected by the momentum resulting from the high speed of operation of any of them, the invention contemplating a mechanism which shall not require attention or repair for long periods of time.

35 These objects and other advantageous ends I secure as hereinafter set forth, reference being had to the accompanying drawings, in which—

Figure 1 is a plan view, on an enlarged 40 scale, showing the construction of a timer made according to my invention; Fig. 2 is a side elevation of the timer shown in Fig. 1; Fig. 3 is a detached perspective view of certain of the parts of the timer; and Figs. 45 4 and 5 are elevations, to some extent diagrammatic, illustrating the operation of the mechanism.

In the above drawings, 1 represents a rotary timing shaft whose speed is the same 50 as, or bears a definite ratio to, that of the engine in whose cylinders the explosive charges are to be ignited. One end of this shaft projects through a relatively fixed circular plate 2 which may constitute the

base of a casing whose detail construction 55 forms no part of the present invention. That portion of said shaft which projects above the top face of the plate has keyed or otherwise fixed to it a collar 3 carrying a ring 4 of insulating material on which is 60 mounted a metal ring 5, and this latter has projecting from its curved surface any suitable number of radial pins 6 depending upon the number of cylinders of the engine. In the present case there are four such pins 65 mounted on the ring 5 at points 90° distant from each other.

Carried by, but insulated from, the base-plate 2, is a flat, more or less segmental, metal plate 7, held in place by screws 8, insulated therefrom by non-conducting washers 7^a and 7^b, and passing through non-conducting bushings so that there is no current flow between the base structure 2 and said plate 7. The latter is provided with a 70 terminal screw 9 electrically insulated from the base-plate and designed for the connection of a conductor forming part of the primary current of an ignition system.

Mounted on the plate 7, immediately adjacent the ring 5, is an angle piece 10 detachably held in place by screws 11 and co-operating with the turned-up edge 12 of the plate 7 to form a narrow guide-way extending substantially perpendicular to the top 85 surface of the plate 2, and in this guide-way is mounted a hooked slide 13. Said slide is characterized by the possession of an incline 35 and a shoulder or hooked portion 14, which, under normal conditions, extends 90 practically perpendicular to the top surface of the plate 2 in the path of movement of the pins 6. From the top end of this shoulder to the adjacent end of the slide piece 13 the incline 35 extends at an angle of about 95 60° to the line of said shoulder and is likewise engaged by the pins 6 when the timing shaft 1 is turned in a direction opposite to that required for them to engage the shoulder.

The slide 13 has through its body portion 100 an elongated slot 15 for the reception of a pivot pin 16 mounted in the parts 10 and 12 and extending across the guide-way in which said slide is movable. The rear end of the 105 slide is forked in the present instance and one branch 17 extends upwardly to provide an arm for the attachment of one end of a

spring 18 whose second end is connected to a pin 19 mounted in the plate 7, the arrangement being such that the spring maintains the forward portion of the slot 15, or that end nearest the hook formed by the incline 35 and the shoulder 14, in engagement with the pivot pin 16.

The lower branch 19 of the fork is bent at right-angles to the general plane of the slide 10 to form an arm designed to co-act with a projecting arm 20 of a lever 21 pivotally mounted on the plate 7 by means of a screw 22. The movement of this lever in one direction is limited by a post 23 projecting upwardly from the top surface of the plate 7, and adjacent its pivot or fulcrum said lever has fixed to it a spring strip 24 of conducting material which is spaced away from its body and whose outer end is bent through 20 an angle of substantially 180° so as to engage the opposite side of said lever. This strip is of spring material and adjacent its end carries a contact piece 25 of some relatively infusible metal, the adjacent part of 25 the lever 21 being offset to allow this spring contact member to move toward it to a limited degree. This lever is normally maintained in engagement with the post 23 by means of a spring 26, having one end in 30 engagement with said lever and its opposite end connected to a post or pin 27 on the base-plate 7. Also fixed to the base-plate is a second segmental plate 28 and this likewise is insulated from it by non-conducting washers 29 and bushings for the screws 30, whereby said plate is held in position. On this latter is a terminal screw 31 and a turned-up portion 32 for the reception of a screw 33 whose outer end terminates in a second contact piece 34 adjacent the contact 25. Said screw 33 is so adjusted that these two pieces are separated by a definite space when the lever 21 is in engagement with its post 23 and under these conditions, the spring 18 holds 40 the slide 13 in its rearmost position with its arm 19 slightly below and out of contact with the arm 20 of the lever 21. If now, the shaft 1 be turned in a clockwise direction, the pins 6 successively engage the shoulder 14 of the slide 13 and move it longitudinally in its slide-way against the action of the spring 18, until the rear end of the slot 15 comes into engagement with the pivot pin 16. Since further movement in a line or 50 plane tangent to a circle concentric with the shaft 1 is now impossible, the slide 13 rotates on said pivot until its shoulder 14 finally disengages the particular one of the pins 6 with which it is engaged, whereupon it quickly returns to its normal position under the action of the spring 18, it being noted that those faces of the pins capable of engaging the shoulder 14 are flat, while the opposite faces are cylindrically curved. At no 60 time during the movement of the slide does

its arm 19 engage the arm 20 of the lever 21, so that there can be no movement of the lever on its pivot. Under the action of each pin, therefore, the slide 13 is moved by a clockwise rotation of the shaft first forwardly in a straight line, then it is caused to turn on its pivot until its shoulder 14 escapes from the pin 6 and then it moves back to its normal position shown in Fig. 2, the contacts 25 and 34 being, of course, out of engagement. When, however, the shaft 1 is rotated in a counter-clockwise direction, the curved surface of the pin 6 first engaging the lever 13 strikes the incline 35 thereof and at once turns it on the pivot pin 16 as 70 indicated in Fig. 5, causing its arm 19 to shortly engage the arm 20 of the lever 21, thus swinging the latter on its pivot screw 22. This movement against the action of the spring 26 continues until the contact piece 80 25 engages the contact 34 at which time the pin 6 is passing off of the highest part of the incline 35 at the upper end of the shoulder 14. As soon, therefore, as this occurs, the spring 18 turns the lever 13 on its pivot into 90 its normal position with a movement which permits the lever 21 to be moved by the spring 26 toward the post 23.

The electric circuit, of which a part is included between the screw 9, plate 7, pivot screw 22, lever 21, spring strip 24, contacts 25 and 34, screw 33, plate 28, and screw 31, is thus made and broken, and the pins 6 and incline 35, as well as the adjustment of the lever arms 19 and 20, are so designed that 100 while the circuit is complete for a sufficient time to produce a spark of the proper intensity in the secondary circuit, there is practically no possibility of the primary circuit being closed for too long a time or accidentally maintained in a closed position, since the action of the pins 6 does not cause the arm 19 to move the lever 21 sufficiently to close said circuit until just before it passes off of the high part of the incline 35. Even 105 though the speed of the shaft 1 be very greatly increased, the action of the pivoted slide 13 is practically constant, it being noted that the movement of the lever 21 toward the screw 33 first permits the contacts 25 and 34 110 to come into engagement, whereupon it continues movement independently of the strip 24 until the slide 13 is disengaged from the actuating pin 6.

At low speeds the same sequence of operations takes place. The sparks are formed at the same times in each revolution of the timing shaft and they continue for the same length of time, there being no vibration or uncertain action due to the inertia of the parts at high speeds, as these latter are relatively light and so mounted that they move through relatively short paths.

By reason of the simplicity of the apparatus it is inexpensive to make and maintain 130

and may be substantial as well as durable, with a constant elimination of uncertainty of action.

I claim:—

5. 1. The combination in a timer of two contacts; an actuating member; and a device consisting of a slide free to move bodily and pivotally and positively movable by said member to cause one of the contacts to periodically engage the other, said slide being mounted to transmit movement directly from said actuating member to one of the contacts.
10. 2. The combination in a timer of an actuating member having a projection; a slide guided to move bodily in one plane under the action of said projection and also free to move pivotally in the same plane; with two contacts mounted to be periodically closed by said slide while it is being positively moved by said projection.
15. 3. The combination in a timer of a rotary actuating member having a projection; a slide movable by said projection and having an elongated slot; a pivot pin passing through the slot; and two contacts of which one is mounted to be positively moved by the slide to engage the other while said slide is being moved by the actuating member in one of two paths.
20. 4. The combination in a timer of a supporting structure having a guide-way; a member slideable in said guide-way and also pivotally movable; an actuating member mounted to cause movement of the slide in either of two paths; and two contact members including a part acted on by the slideable member while it is being moved by the actuating member in one of its paths, to cause engagement of said contacts.
25. 5. The combination of a supporting structure having a guide-way; an actuating member rotatable in either of two directions and having a projection; a slide operative in the guide-way under the action of said projection and having a slot; a pin passing through the slot; a spring acting on the slide to normally hold it in a definite position; a fixed contact; with a relatively movable contact co-operating therewith and including a portion placed to be operatively engaged by the slide while the latter is being positively moved by the actuating member.
30. 6. The combination in a timer of a rotary shaft having a projection; a slide having a hooked portion placed to be engaged by said projection and provided with an elongated slot; a pivot pin passing through the slot; a spring normally holding the slide in a definite position; and two contacts of which one includes a portion actuated by the slide while the latter is being moved by the projection.
35. 7. The combination in a timer of a rotary member having a projection; a slide having a shoulder and an inclined portion of which one is engaged by the projection when the shaft turns in one direction and the other is engaged by said projection when the shaft turns in the opposite direction; a pivot pin 70 passing through an elongated slot in the slide; a lever moved by the slide when the shaft projection moves the latter in one path but operatively free from said slide when the shaft rotates in the opposite direction; a 75 fixed contact; and a co-operating contact carried by the lever.
40. 8. The combination in a timer of a rotary shaft having projections; a supporting structure having a guide-way; a slide movable in the guide-way and having an elongated slot, said slide including a shoulder and an inclined portion, both placed to be engaged by said projections; a pivot pin passing through the slot of the slide; a 80 spring normally holding the slide in a definite position; two contacts; with a lever carrying one of said contacts and placed to be turned on its pivot to cause engagement of the contacts only while the slide is being 85 positively moved by the shaft in one of two definite paths.
45. 9. The combination in a timer of a rotary shaft having projections; a supporting structure having a guide-way; a slide operative 90 in the guide-way and having an elongated slot; a pivot pin passing through the slot; a spring normally holding the slide with one end of its slot in engagement with the pivot; said slide having a shoulder and inclined 95 portion both in the path of movement of the projections; a fixed contact; and a contact lever co-operating therewith mounted to be positively actuated by the slide to close the contacts when the incline of said slide is engaged by a projection of the shaft and to be unaffected by the slide when the shoulder thereof is engaged by the projections.
50. 10. In a contact device a pivoted lever; a stop limiting its movement; a head on 100 said lever having a cam face through which it is normally operated in one direction and an abutting face through which said head is operable in the opposite direction; a second lever having a part in the line 105 of movement of the first lever at one point in the latter's advance movement whereby in the forward movement of the first lever the second lever will be positively advanced to close the circuit; a stop limiting movement of said second lever; with tension means to return both levers against their stops after they have been moved therefrom.
55. 11. In a contact device a pivoted lever 110 adapted for primary actuation; a tension device tending to hold said lever in inoperative position; a stop limiting the movement of said lever by said tension device; a second lever mounted on a fulcrum inde- 115
60. 12. In a contact device a pivoted lever 120 adapted for primary actuation; a tension device tending to hold said lever in inoperative position; a stop limiting the movement of said lever by said tension device; a second lever mounted on a fulcrum inde- 125
65. 13. In a contact device a pivoted lever 130 adapted for primary actuation; a tension device tending to hold said lever in inoperative position; a stop limiting the movement of said lever by said tension device; a second lever mounted on a fulcrum inde-

- pendent of that of the first lever and having an arm which extends adjacent and in the line of movement of an arm of said first lever, whereby said arm in the advance 5 movement of said first lever will tilt the second lever into position to close the circuit; a tension device arranged to retract the second lever; and a stop arranged to limit the movement of the second lever by 10 said tension device.
12. The combination of an actuating member; a lever periodically moved thereby; a second lever independently mounted on a fulcrum relatively distant from that 15 of said first lever in position to be turned on said fulcrum by the first lever while the latter is being moved by said member; a fixed contact; and a second contact carried by the second lever in position to engage 20 the fixed contact while said levers are being positively moved by the actuating member.
13. The combination in a timer of two contacts; an actuating member; with a slide pivotally as well as bodily movable by said 25 member and mounted to positively force said contacts into engagement while being moved by the actuating member.
14. The combination in a timer of two contacts; a member pivotally and bodily 30 movable, mounted to cause closing of said contacts while it is being turned from its normal position against a retracting force; and a second lever for periodically turning and thereafter releasing said first member.
15. The combination in a timer of two contacts, a lever mounted to cause closing of said contacts when moved in one direction; an actuating member rotatable in either of two directions; with a second 35 lever mounted to be turned on its fulcrum by said actuating member when this latter is rotated in one direction and thus cause movement of the first lever while being so turned, said second lever being placed to 40 be moved bodily by the actuating member when this is turned in the opposite direction and being then without operative effect on the first lever.
16. The combination of a fixed contact; 50 a movable supporting structure including a second contact; a rotary cam; an independent and bodily movable intermediate member mounted to engage said structure
- to cause closing of the contacts while it is being moved by said cam; and a spring for 55 returning said intermediate member to its normal position.
17. The combination in a timer of an actuating member; an intermediate member; a contact-closing member; with two 60 tension devices respectively operative on the intermediate and contact-closing members, both of said devices being operative to return the intermediate member to its normal position after it has been displaced 65 by the actuating member.
18. The combination in a timer of an actuating member; an intermediate member consisting of a bodily movable slide having a cam face placed to be engaged by said 70 actuating member; a contact-closing member actuated by the slide; with two tension devices respectively operative on the slide and on the contact-closing member, both of said devices being operative to return 75 the slide to its normal position after it has been displaced therefrom by the actuating member.
19. The combination in a contact device of a member having a slide formed with a cam face through which it is normally operated in one direction and an abutting face through which it is operated in the opposite direction; a second member having a part in the path of movement of the first member while its cam face is being operated on; and contacts placed to be closed by said second member while it is being moved by the first member.
20. The combination in a timer of two contacts; an actuating member; and a device consisting of a slide free to move bodily and pivotally and positively movable by said member to cause one of the contacts to periodically engage the other, said slide being mounted to transmit movement directly from the actuating member to one of said contacts while it is being moved by said member.
- In testimony whereof, I have signed my name to this specification, in the presence of two subscribing witnesses.
